HUBERT DRACHE, OF NEW YORK, N. Y.

SURGICAL INSTRUMENT

Application filed June 10, 1931: Serial No. 543,358.

This invention relates to surgical instruments, more particularly to improvements in surgical knives for use by physicians and surgeons in performing operations.

It is an object of the invention to provide a surgical knife simple in structure in which blades of any size for use in performing surgical operations of any kind can be easily attached and as deeper incisions are made in the subject being operated upon, blades of different length can be easily and quickly attached to the knife handle.

Another object of this invention is to provide a surgical knife which can be easily taken apart for replacing or substituting a blade of the same or different size and which can be quickly assembled when and as blades of different length are required during an operation.

Still another object of this invention is to construct a surgical knife in which the blades can be interchangeably used and firmly engaged to the handle, thereby obtaining a firm, one-piece construction.

This invention in its preferred form embodies a knife blade and a pair of opposite side plates constituting the handle for holding the blade between their inner faces and a pivoting stud on one of the plates for firmly engaging the blade and the other plate, and means for preventing the plates from sliding angularly with respect to each other.

Further objects and features of this invention will become apparent in the hereinafter detailed description and claim.

Referring in detail to the drawing wherein is shown one simple and practical preferred embodiment of the invention in which similar reference characters designate corresponding parts throughout the several views:—

Figure 1 is a side elevation presenting the embodiment in its assembled form;

Fig. 2 is a longitudinal edge view of Fig. 1;

Fig. 3 is a plan view of the elements comprising the embodiment shown in Figs. 1 and 2;

Fig. 4 is an enlarged view looking on line 4—4 of Fig. 1; and

Fig. 5 is an edge view looking in the direction of 5—5 in Fig. 1.

In the drawing is shown a knife blade 10 having a thin razor-like cutting edge 12, and a thickened back edge 13. The edges of the body portion of blade 10 gradually taper and are constricted at about the middle portion of the blade and then spread out into a shank 14. The sides of the shank are recessed, as shown in Fig. 3, so as to leave laterally extending edge portions 15 at the upper end of the shank and laterally extending, oppositely disposed lugs 16 at the end of the shank. Extending along and in the same plane as the longitudinal axis of the blade is a perforation 18 preferably elliptical in form.

The handle of the knife consists of two mutually separable parts. One of the parts is an opposing side plate 20 generally of a die-pressed metal with the ends beveled or rounded, as shown in the drawing, and a pivoting stud 22 punched into the inner face of the plate at a point on the longitudinal axis adjacent the upper end of the plate. The body 24 of this stud is substantially cylindrical-shaped (Fig. 4), while the head 26 is flattened and substantially elliptical-shaped with its major axis running at right angles to the longitudinal axis of the plate. The position of the stud on the plate is such that it acts both as a pivot or fulcrum and a clamping means, while the plate itself acts as a lever. On one of the longitudinal edges of the plate and at its lower part is a curvate-shaped recess 28 to allow for easy insertion of the fingernail, by the user of the knife, upon the midsection of the handle when it is desired to be taken apart. The inner face of the plate also contains a depression or an indentation 30 on a point along the longitudinal axis but at the lower portion of the plate so as to provide contact with the other part of the handle hereinafter described. The outer face of plate 20 is knurled or milled at its upper portion 32 to provide proper surface contacting means for firmly retaining the plate between the fingers.

The remaining portion of the knife handle contains another opposing side plate 34 whose interior face is partly channeled, as shown

in Fig. 3, so as to leave vertically arranged flanges 36 on either side of the inner face. The flanges are of gradually increasing height toward the upper part of the plate and end abruptly at a point 38 just below the upper end of the plate 34. A groove is at 40 in the same plane to allow for the fitting of the lugs 16 of the blade shank 14 therein and of the seating of the lateral extension 15 against the end 38 of the flanges. The width of the top portion of the channel 34 is of slightly greater dimension than that of the shank 14 so that when the blade 10 is attached on to the plate 34, the shank 14 fits snugly into the channel of the plate, the lugs 16 being set in grooves 40 and the upper lateral extensions 15 fit against the end of the flanges at 38. By such an arrangement a closely fitting engagement is effected between the lateral extensions 15 with the ends 38 and the lugs 16 in the grooves 40 of the plate 34. In this particular embodiment there is slight tolerance or clearance between the shank 14 and the channel of the plate to allow for easy insertion or detaching of blades from the plate.

Between the flanges 36 and at the top end of the plate 34 is a perforation 42 situated on the longitudinal axis of the plate and at a point between the set-off flanges 39. The perforation on the inner channel face of the plate 34 is of elliptical shape, as indicated by 44, whereas the outer face of the plate is countersunk to effect the appearance of a circle 46. The perforation as seen by looking at the outer face of the plate 34 has the appearance of a circle gradually diminishing into an ellipse in which the major axis of the ellipse is in the same plane as the longitudinal axis of the plate 34, as shown in Figs. 1 and 3. In this manner there is a gradually inclined wall from the periphery of the circular countersunk portion of the elliptical opening. By the construction of such countersunk portion and of the head 26 of stud 22 being curved toward the main axis of the stud, a camming action is effected when the plates are brought into combined relation, as shown in Fig. 1. It is to be noted that when the shank of the blade is contained between the plates, the camming action formed by drawing the plates in circular relation toward each other tightly clamps the shank, thereby preventing lateral or circular displacement of the blade with respect to the plates.

The perforations 18 and 42 of the shank 14 and plate 34, respectively, are adapted to receive the pivoting stud 22 on the plate 20, so that when the blade has been placed in its proper position on plate 34, both plates 20 and 34 are brought in side opposing juxtaposition, as shown in Fig. 2. The stud 22 on the plate 20 is inserted in the perforations 18 of the shank 14 and 42 of plate 34 with its major axis in the same plane as the ellipti-

cal projections of the blade 10 and plate 34. Both plates at this point would be at right angles to each other, the stud 22 acting as a pivot. After the stud has been inserted into the perforations 18 and 42, the plates may then be moved relatively towards each other in angular displacement on the pivoting stud and brought into side opposing position, as shown in Figs. 1 and 2. This turning of the plates relatively toward each other is through 90° and causes the stud by the formation of its head and body portion to draw both plates together and thereby clamp and firmly engage the blade 10. It is to be noted that plate 34 may be firmly held while the other plate 20, after being brought into right angle position with the first plate, is turned through 90°.

On the same axis as the perforation 42 but at a point towards the lower end of the plate 34 is a pin 48 extending from the surface of the plate which fits into the depression 30 of the side opposing plate 20 when the knife is assembled. The engagement of pin 48 in depression 30 prevents the plates from sliding over each other, thereby preventing the blade of the knife from being moved in the channel of plate 34. It is to be noted that plate 34 also has a curvate depression 50 along the lower portion of one of its edges so that when the knife is assembled, the blades can be easily disconnected by insertion of the fingernail of the user so as to slide the plates apart from each other a distance equal to the length of the pin 48, whereby the plates are then moved relatively away from each other and the blade retained by the plate 34 is easily detached and replaced. The other face of the plate 34 is also milled or knurled at its upper portion 52 so that when the knife is assembled a portion of the handle can be firmly grasped between the fingers of the surgeon for properly using the knife.

From the foregoing description, it will be seen that blades of any length or size can be firmly attached to the handle herein described, thus eliminating the use of many knives with blades permanently attached to the handle. Furthermore by the use of the herein described embodiment, only the blades need be sterilized, thereby effecting economy of time and amount of material for use for assembling the knife.

It is to be noted that the knife herein described can be easily and quickly assembled and that the component parts of the handle are firmly held together without any chance of the blade becoming loosened from the handle during the use of the knife. In the embodiment of the invention the blade is firmly gripped between the handle plates to prevent lateral, longitudinal, or circular movement of the blade within the handle, the firm grip of the blade being a highly desirable feature, particularly where surgical knives

are used in delicate operations. By the arrangement of the constructional feature of the stud on one plate and inserting it into the perforations of the blade shank fitted into the channel portion of the other plate, there is effected not only a pivoting action in assembling the knife, but also an efficient clamping action whereby the shank of the blade is depressed more firmly into the channel and grooves of one of the plates.

While certain specific constructional features of the preferred embodiment have been described, it is to be understood that many modifications may be made without departing from the spirit and scope of the invention as defined in the hereinafter appended claim.

I claim:

A surgical knife comprising a blade having a recessed shank portion with an eye and oppositely disposed lugs projecting laterally therefrom, a channeled plate having upwardly extending flanges offset from the side of the plate on the longitudinal edges thereof for accommodating the recessed shank portion and transverse grooves in the sides of the plates to permit the lugs on the shank portion to abut the offset ends of the flanges and also make engagement with the grooves thereof, said channeled plate having a perforation whose opposing side face is congruous with the perforation on the blade and whose outside face comprises a countersunk circular depression with gradually progressive depth toward the center of the perforation, a complementary plate for covering the channeled plate having a stud with an elliptical shaped head, and a cylindrical body projecting from said plate, passing through the perforations of the blade shank and the side opening plate whereby upon angular displacement of one plate to the other around the stud as a pivot, a clamping action is effected and the plates are contracted together for rigidly retaining the blade therebetween to prevent lateral and angular displacement of the blade, and means on the second plate for retaining the plates together.

In testimony that I claim the foregoing as my invention, I have signed my name hereto.

HUBERT DRACHE.
